UNITED STATES PATENT OFFICE

EMIL KOEB, OF TUCKAHOE, NEW YORK, ASSIGNOR, BY MESNE ASSIGNMENTS, TO
PERFECT WINDOW REGULATOR CORPORATION, OF LONG ISLAND CITY, NEW YORK,
A CORPORATION OF DELAWARE.

WINDOW REGULATOR.

Application filed March 15, 1923. Serial No. 625,291.

To all whom it may concern:

Be it known that I, EMIL KOEB, a citizen of the United States, and a resident of Tuckahoe, in the county of Westchester and 5 State of New York, have invented certain new and useful Improvements in Window Regulators, of which the following is a specification.

My invention relates to window regulators 10 for raising and lowering windows and it is particularly adapted in its application to windows of vehicles such as automobiles.

The principal object of the invention is 15 the production of a window regulator of simplicity of construction and ease of operation.

A further object of the invention is the production of a window regulator having the above characteristics which shall contain 20 simple and effective means for holding the window against movement in either direction when power is applied thereto.

Further objects and advantages will appear from the accompanying description, 25 the invention consisting in the novel parts and combinations thereof hereinafter more particularly described and then specified in the claims.

In the accompanying drawing illustrating 30 a practical embodiment of the invention:

Fig. 1 is a front elevation of a portion of a window showing the invention with parts removed.

Fig. 2 is a horizontal cross-section taken 35 through the window.

Fig. 3 is a cross-section (partly in elevation) of a part of the device.

Fig. 4 is a rear elevation of the part shown in Fig. 3.

40 Referring to the drawing:

The side members of a window frame are indicated at 1, these members being provided with channels or guideways 2 receiving and supporting a window which is slideable vertically therein. Said window 3 has a strip 4 secured in any desirable manner to the lower edge thereof, this strip being provided with a horizontal slot 5 therein.

50 A support 6 is secured to one of the side members 1 and is provided with upper and lower extensions 7 and 8 respectively. The upper extension has a toothed member 9 comprising a gear pivoted thereto while the

lower member has an operating arm 10 pivoted thereto to which is secured a toothed member or gear 11 meshing with the gear 9. It will be noted that the diameter of the gear 11 is appreciably greater than that of the gear 9 and contains an appreciably greater number of teeth.

The end of the arm 10 is provided with a roller 12 received by the slot 5 and it is also provided with an extension 13 to which are secured the springs 14, the other ends of said springs being secured to the extension 8. The function of said springs is to counterbalance the weight of the window 3 and to assist in the raising thereof.

An annular box or bearing 15 is fastened 79 to the extension 7, said box receiving and supporting a rotatable hub member 16 provided with reduced members 17 and 18 which extend through the wall of the extension 7 and the front wall of the box respectively as shown in Fig. 3. The extension 17 terminates in a relatively small pinion 19 shown in the present instance as provided with three teeth. This pinion meshes with the gear 9. The extension 18 terminates in a manual control member or shaft 29 receiving a handle or crank 20. It will be noted that the radius of the pinion 19 is appreciably smaller than the radius of the hub member 16 and that the pinion is considerably smaller than the gear 9. If so desired the lower portion of the window may be covered by upholstery 21 or any other suitable material so that all the mechanism is hidden from view with the exception of the handle 20. I prefer also to interpose spring washers 22 between the box 15 and the hub member 16 which act to eliminate rattling and assist in the operation of the device.

To raise or lower the window the handle is rotated in the proper direction, the motion being transmitted through member 16, pinion 19, gear 9, gear 11, operating arm 10 and the roller 12 which slides in slot 5 as has been explained. When the handle is released the window is automatically locked against movement when power is applied to the window itself because of the reduction gearing heretofore explained, together with the fact that the comparatively large size of the hub member 16 as respects the pinion

- 19 provides a large frictional surface for contact with the box 15 which acts to resist such movement. In other words the mechanical disadvantage of the construction 5 described produces a resistance to a movement of the window too great to be overcome by power applied thereto, although the window is easily operated when power is applied to the driving member or handle.
- 10 1. What I claim as my invention is:—
1. In a window regulator, an operating arm engaging the window, a handle, a hub portion connected to said handle, a bearing for said hub portion, a pinion connected 15 to said hub portion and having a radius appreciably smaller than the radius of said hub portion and means engaging said pinion and arm to permit movement of the window upon actuation of the handle.
  2. In a window regulator, an operating arm engaging the window, a handle, a hub portion connected to said handle, a bearing for said hub portion and a pinion connected to said hub portion and having a radius 25 appreciably smaller than the radius of said hub portion, said pinion being operatively connected to said arm to permit movement of the window upon actuation of said handle.
  3. In a window regulator, an operating arm engaging the window, a rotatable handle, a hub portion connected to said handle, a bearing for said hub portion, means connecting said hub portion and said arm to 35 permit movement of the window upon actuation of said handle and spring means pressing against said hub portion in a direction transverse to the axis of rotation of said handle.
  4. In a window regulator, an operating arm engaging the window, a handle, a pinion, a gear connecting said pinion and said operating arm and connecting means between said pinion and said handle, said connecting means providing a frictional resistance to movement of the window when power is applied thereto and having a diameter appreciably greater than the diameter 45 of said pinion.
  5. In a window regulator, a rotatable shaft, a member mounted for rotation with said shaft and provided with an enlarged frictional contact surface, a fixed member

having a cooperating frictional contact surface, means operated by said shaft and 55 including a plurality of rotatable members for operating said window, a spacing member positioned for free movement between said member and said fixed member, and means for counterbalancing the weight of 60 said window.

6. In a window regulator, a support, a rotatable shaft carried by said support and including a friction member, a fixed member carried by said support and positioned 65 to be engaged by said friction member, window operating means including a plurality of rotatable members, means connecting said shaft and window operating means, said last-mentioned means producing a thrust on said shaft which increases the friction between said friction member and said fixed member, and means for counterbalancing the weight of said window.

7. In a window regulator, a rotatable 75 pinion, an enlarged member mounted for rotation with said pinion and having a frictional contact surface of a diameter relatively larger than that of said pinion, a friction member having a contact surface 80 cooperating with that of said enlarged member, a gear co-acting with said pinion for operating said window, and means for counterbalancing the weight of said window.

8. In a window regulator, a window operator including a rotatable hub member having an enlarged peripheral bearing surface, a manual control member connected to said hub member for rotating the same and 90 a relatively small pinion, said hub member, manual control member and pinion being rigidly secured to one another for simultaneous rotation, a fixed annular bearing member encircling said hub member 95 and provided with means for frictional engagement with the peripheral bearing surface of said hub member, and means for moving said window upon rotation of said hub member, said means including a gear 100 meshing with said pinion.

Signed at New York, in the county of New York and State of New York, this 13th day of March A. D. 1923.

EMIL KOEB.
